UNITED STATES PATENT OFFICE

RALPH A. TUCKER, OF JACKSON, MICHIGAN

KEY CLIP

Application filed November 3, 1930. Serial No. 493,143.

This invention relates to key clips and has for an object the provision of a clip for holding keys in a manner to keep the latter ready for use, the invention being especially designed for holding the ignition and door keys of an automobile.

Another object of the invention is the provision of a clip which will hold keys in a compact form so that they may be conveniently carried, and which in addition, will prevent knocking and rattling of the keys against the instrument board of an automobile when the key is in the ignition lock, so that objectionable noise and damage to the board from this cause will be avoided.

With the above and other objects in view, the invention further includes the following novel features and details of construction, to be hereinafter more fully described, illustrated in the accompanying drawings and pointed out in the appended claim.

In the drawings:

Figure 1 is an elevation illustrating the use of the invention.

Figure 2 is a side view of the clip.

Figure 3 is an edge view with the parts in the position shown in Figure 1.

Figure 4 is an edge view of the clip.

Figure 5 is a plan view of the blank from which the clip is made.

Figure 6 is a section on the line 6-6 of Figure 1.

Referring to the drawings in detail wherein like characters of reference denote corresponding parts, the clip, which is formed of resilient metal, comprises side walls 10 and a rear wall 11, which connects the side walls along one edge.

The side walls are substantially semi-circular at one end as shown at 12 so as to receive the circular ends 13 of keys of the type usually employed for the ignition locks and doors of automobiles. The side walls are preferably shaped as shown in Figures 1 and 2 so as to provide substantially tapered portions

14 at their other ends, and the shanks of the keys are adapted to be positioned between these substantially tapered portions which are provided with inwardly curved recesses to expose the shanks to provide a finger hold 50 for the keys as shown in Figure 1 of the drawings.

The side walls are formed with inwardly extending projections or teats 15 which are arranged in opposed relation as shown in 55 Figure 6 of the drawings, and these projections or teats are adapted to enter openings 16 provided in the keys as shown in Figure 6. These projections or teats will thus form a fulcrum upon which the keys may be swung 60 into and out of the clip, after the manner of the ordinary pocket knife.

As the walls of the clip are of a resilient character, they will frictionally grip the keys so that the ignition key may be inserted in 65 the lock of an automobile and the clip will be prevented from dropping upon the instrument board. In addition, the shoulder 17 provided at one end of the rear wall 11 will act as a stop to limit relative pivotal movement 70 of the keys and clip in one direction.

In Figure 5 of the drawings there is illustrated the blank from which the key is made. This blank is shaped as shown and is bent along the dotted lines 18 so as to provide the 75 opposed side walls and the rear connecting wall.

The invention is susceptible of various changes in its form, proportions and minor details of construction and the right is here reserved to make such changes as properly fall within the scope of the appended claim.

Having described the invention what is claimed is:

A key clip comprising spaced parallel arranged side walls substantially semi-circular at one of their ends and substantially tapered toward their opposite ends to present a substantially key shape configuration, a straight rear wall connecting and bridging the side 85 90

walls at one of the longitudinal edges thereof, opposed spaced teats extending inwardly from the substantially semi-circular portions of the side walls and cooperating with each other to provide key pivots, a stop shoulder formed by one end of the rear wall to limit relative pivotal movement of keys received by the teats, and the substantially tapered portions being provided with curved recesses extending into the free edges thereof to expose the shanks of the keys whereby the latter may be grasped for moving the keys on the teats from the clip.

15 In testimony whereof I affix my signature.

RALPH A. TUCKER.
